CLAIM

The ornamental design for a fishing pole holder with strike alert light, as shown and described.

DESCRIPTION

FIG. 1 is a perspective view of a fishing pole holder with strike alert light showing my new design it being understood that FIGS. 1, 2, 3, 4, and 5 are shown broken away for convenience of illustration;

FIG. 2 is a rear elevational view thereof;

FIG. 3 is a side elevational view thereof;

FIG. 4 is a front elevational view thereof;

FIG. 5 is an elevational view of the opposite side of that shown in FIG. 3;

FIG. 6 is a top plan view thereof;

FIG. 7 is a bottom plan view thereof; and,

FIG. 8 is a top side perspective view thereof, the broken lines illustrating a fishing pole and fishing line are for illustrative purposes and form no part of the claimed design.
